UNITED STATES PATENT OFFICE.

CARL R. LENDLE, OF CHICAGO, ILLINOIS.

GARMENT STEAMING AND PRESSING MACHINE.

Application filed June 3, 1919, Serial No. 301,435. Renewed July 26, 1922. Serial No. 577,739.

To all whom it may concern:

Be it known that I, CARL R. LENDLE, a citizen of the United States, residing at Chicago, in the county of Cook and State 5 of Illinois, have invented new and useful Improvements in Garment Steaming and Pressing Machines, of which the following is a specification.

This invention relates to machines or apparatus for steaming and pressing garments, and its object is to provide a machine of this kind which is simple in construction and highly efficient in operation, and easily operated.

15. The object stated is attained by means of a novel combination and arrangement of parts to be hereinafter described and claimed, and in order that the same may be better understood, reference is had to the accompanying drawings, forming a part of this specification.

In the drawings,

Figure 1 is a front elevation of the machine;

25. Fig. 2 is a face view, partly broken away, showing the presser head;

Fig. 3 is a plan view, partly broken away, showing the work-supporting buck;

30. Fig. 4 is a view similar to Figure 1 with the parts in another position, and

Fig. 5 is a horizontal section on the line 5—5 of Figure 4.

Referring specifically to the drawings, 10 denotes a presser head which is positioned 35 above the work-supporting member or buck 11, and is pivotally supported to swing down and engage the garment on the latter for pressing the same. The buck 11 is supported by a stand 12 of any suitable design, and 40 the presser head 10 is carried by an arm 13 having a pivotal connection with the stand at 14. The presser head 10 is operated in the usual manner by a foot pedal or lever 15 having a link connection 16 with the arm 13. These parts are all arranged in a well-known manner and a detailed description 45 thereof is therefore not necessary, it being understood that the presser-head swings down to engage the work on the buck 11 when the pedal 15 is depressed. A counter-weight 17 is mounted on the link 16 to elevate the presser head when the pedal 15 is released.

The presser-head 10 is hollow and contains a coiled steam pipe 18 having perforations for escape of the steam, and the bottom

or working face of the presser-head is also perforated for the same purpose. The buck 11 is also hollow and contains perforated steam pipes 19, and its top or work-holding 60 surface is perforated to permit escape of steam. The buck 11 and the presser head 10 are padded as usual.

At 20 is shown a steam supply pipe having a flexible connection 21 with the pipe 18, 65 and a similar connection 22 with the pipe 19.

To the front side of the stand 12, beneath the buck 11 is rigidly secured an outstanding shelf 23, and to the opposite, or rear side of the stand, is hinged, as shown at 24, a 70 shelf 25 having at its outer longitudinal edge an upstanding guard wall 26 which is hinged, as shown at 27, so that it may be folded to extend straight out from the shelf 25. The hinge connection 27 is sufficiently 75 stiff so that the guard wall 26 remains upright after it is swung to that position.

To one end of the stand 12 is hinged, as shown at 28, a third shelf 29 having its outer end slotted, as shown at 30 to clear the pedal 80 15 when it is swung down as shown in Figure 1.

To the rear longitudinal edge of the shelf 29, is hinged, as shown at 31, an extension shelf 32 having a guard wall 33 similar 85 to the wall 26 and adapted to come in alignment therewith when the shelves 25 and 32 are swung into supporting position as shown in Figures 4 and 5. The various shelves hereinbefore described are all at the same 90 level when they are swung into supporting position.

To fold the shelves 25, 29 and 30, the wall 26 is folded to extend straight out from the shelf 25 and said parts are swung down 95 to come alongside the back of the stand 12 as shown in Figure 1. The shelf 29 is then swung down to come alongside the end of the stand 12, and as this shelf carries the shelf 32, the latter is swung down with it. The wall 33 is also folded to extend outwardly from the shelf 32, and these two parts are then folded back to come in front of the folded shelf 25 and its guard wall 26, as shown in Figure 1, and dotted in Fig. 5.

The shelf 28 is held up in supporting position by suitable props 34, and similar props are provided for the shelf 25. The shelf 32 is held up by being stiffly hinged to the shelf 29.

105 The presser head 10 is of greater length than width, and it is hinged or pivoted to

swing in a plane running in the direction of its longer dimension. By thus mounting the presser head so that it swings from one end, the work is left free to hang from both 5 sides of the buck 11, which is very desirable when pressing skirts, and the buck is also rendered more accessible for placing the work thereon, and for removing it. If it is desired to support that portion of the garment 10 which hangs down from the buck 11, the shelves 25, 29 and 32 can be readily swung up. This arrangement is useful to hold plaited materials against becoming extended, or long robes from touching the 15 floor. The buck 11 can also be used alone for steaming garments.

I claim:

1. In a garment pressing machine, a supporting stand, a work holding member carried by the stand, a shelf hinged to one end

of the stand, a shelf hinged to one side of the stand, and an extension shelf hinged to the end shelf, said end and side shelves being foldable to seat alongside the stand, and the extension shelf being foldable to come alongside the folded side shelf. 25

2. In a garment pressing machine, a supporting stand, a work holding member carried by the stand, a shelf hinged to one end 30 of the stand, a shelf hinged to one side of the stand, an extension shelf hinged to the end shelf, said end and side shelves being foldable to seat alongside the stand, the extension shelf being foldable to come alongside the folded side shelf, and upstanding 35 guard walls hinged to the side and extension shelves, and foldable to come in alinement therewith.

In testimony whereof I affix my signature.
CARL R. LENDLE.
